UNITED STATES PATENT OFFICE.

JAMES ROBERT ROBINSON, OF NEWCASTLE-ON-TYNE, ENGLAND.

TICKET-STAMP.

SPECIFICATION forming part of Letters Patent No. 233,807, dated October 26, 1880.
Application filed July 27, 1880. (No model.) Patented in England February 25, 1880.

To all whom it may concern:

Be it known that I, JAMES ROBERT ROBINSON, a subject of the Queen of Great Britain, residing at Newcastle-on-Tyne, England, have 5 invented certain Improvements in Stamps or Apparatus for Dating and Numbering Railway-Tickets, and for other like purposes, (for which I have obtained a patent in Great Britain, No. 831, 25th day of February, 1880,) of 10 which the following is a specification.

My invention relates to certain improvements in the construction of hand-stamps for railway-tickets and similar articles, as more 15 fully described hereinafter, reference being had to the accompanying drawings, in which—

Figure 1 represents a side elevation of a machine constructed according to my said invention. Fig. 2 is a front elevation, and Fig. 3 a 20 sectional side elevation, of the same; and Fig. 4 is a sectional plan of the under side of the machine. The remaining figures are detail 25 views of parts and modifications of parts hereinafter referred to.

A is a casting forming the support for the 25 stamping apparatus. To the top of this support, at a, is jointed a rocking frame or block, B, which carries a disk, C, constituting the day-dating stamp, the said disk having type e round its periphery, bearing numbers arranged 30 in order from, say, 1 to 31—that is to say, the full numbers of days in any month. The disk C is mounted so as to be capable of turning upon a spindle, c', carried by the rocking frame B, and is supported between the arms 35 b b' of the frame B, as shown in Fig. 2. In order to keep the disk in position after the daily adjustment has been effected, a pin, D, is provided, which is carried by a bracket, d, upon the arm b, the said pin engaging in holes 40 or notches e' arranged round the side of the disk, one hole or notch being provided for each number, as shown in Fig. 3. The pin D may be maintained in engagement with the holes by means of a spiral spring, d', as shown, applied to a modification of my said invention, 45 Fig. 8, hereinafter referred to.

The type for stamping the letter or letters representing the month of the year upon the ticket is shown at E. It is arranged at one 50 side of the disk C in a recess, e, formed in the lower part of the arm b of the rocking frame

B, the said type being held securely within its recess by the plate e' and thumb-screw e².

F is the type for stamping the numbers representing the year upon the ticket. It is arranged at the other side of the disk in a similar manner to the month-dating type within a recess formed in the other arm, b', of the frame B, the said year-dating type being held securely by a thumb-screw, f. The rocking 60 frame B thus carries the whole of the type for stamping the month, day, and year, the type being arranged side by side in a line, as shown in Fig. 2 and in the sectional plan of the under side of the apparatus in Fig. 4. Depending from the rocking frame B is a similar rocking piece or block, G, hinged at g to the frame B, the extremity g' bearing against the stop a' formed at the base of the casting A, as shown in Figs. 1 and 3. An aperture or guide, 70 g², is provided at the top of the block G for the reception of the ticket or other card to be stamped. In Fig. 3 a card marked X is represented as inserted in the aperture in position to be stamped.

The apparatus for supplying ink to the type is arranged in the following manner: Two receptacles, H, are fixed, one at each side of the frame B, with spindle h passing through them. Upon these spindles are mounted reels of tape 80 h', Fig. 4, the tape being in one length, and so arranged as to be capable of being wound off from one reel to the other, while the strip h of tape, for the time being situated between the two reels, passes over the rollers h² and 85 2, 3, and 4. The tape is saturated with ink, reels of tape thus constituting ink-reservoirs, whereby separate ink-receptacles are dispensed with.

The spindles h, carrying the reels h' of tape, are provided with cranked handles 1 1, by which the tape is moved over the face of the type in order to supply a fresh surface of ink, the tape being during the process of stamping 95 interposed between the type and the ticket to be stamped, as shown clearly in Figs. 3 and 4, in which latter figure the tape is represented as broken away in order to render the type visible.

Springs y may be provided as shown in Fig. 4, the same bearing against the sides of the

reels, so that a certain amount of tension may be applied to the tape as it passes over the type.

If desired, the movement of the tape may be effected automatically by the following arrangement: On one of the spindles h is secured a ratchet-wheel, h^6 , and mounted loose on the said spindle is a pawl-holder, h^4 , carrying a pawl, h^5 , which engages with the teeth of the ratchet-wheel h^6 . By the movement of the rocking frame B in the act of stamping, as hereinafter more fully described, the frame B forces the pawl-holder h^4 up an inclined plane, a^2 , Figs. 1 and 2, fixed to the side of the apparatus, whereby a feed is imparted to the pawl h^5 . Upon the return movement of the rocking frame B, after the operation of stamping, the pawl is caused, by the action of a rod, h^7 , within a tube, h^8 , Figs. 1, 2, and 5, to impel the ratchet-wheel h^6 , the said rod being forced out by a spring, h^9 , Fig. 2, which has been compressed during the forward movement of the rocking frame B. A motion of partial rotation is thus imparted to the reels of tape, whereby the strip of tape between the two reels is caused to move over the face of the type, so as to present a fresh-inked surface.

In lieu of the above arrangement for effecting the movement of the tape automatically, the pawl-holder h^4 may be carried upon a rod or guide, i , which is fixed due at an angle with the side of the apparatus and passes through a slot, I, formed in the said pawl-holder, as shown in the detailed views, Figs. 6 and 7.

Upon the forward movement of the rocking frame B the pawl-holder is caused to follow the inclination of the rod or guide i , whereby a feed is given to the pawl, which, as in the first arrangement on the return movement of the rocking frame, is caused to impel the ratchet-wheel and impart thereto a motion of partial rotation, whereby movement is communicated to the tape, as hereinbefore described.

The operation of stamping a ticket by the use of this machine is carried out in the following manner: The number upon the disk C, corresponding to the proper day of the month, is brought round into position—that is to say, into line with the two sets of type E F, one at each side of the disk—the pin being inserted in the hole or notch corresponding to the required number, whereby the disk is held securely in position. Assuming the letters and figures of the two sets of type at the sides of the disk C to be set according to the proper month and year, respectively, the apparatus is ready to stamp the ticket. The ticket is inserted in the aperture g^2 , the two hinged blocks or frames B G being at the same time urged forward by the fingers of the operator, by which movement the jaws of the said hinged blocks or frames at g , Fig. 3, are brought together, the type upon the frame B thus being brought into contact with the ticket resting upon the top of the block or frame G, whereby an impression is stamped upon the ticket through

the intervention of the ink-supplying tape, as hereinbefore described, the blocks or frames being returned to their normal position under the action of a spring, 2. Thus, according to this invention, in the operation of the machine the disk carrying the day-dating type is moved round into position once daily, the month-dating type is altered monthly, and the year-dating type is altered yearly, whereby great simplicity in the operation of the machine is attained, and the liability of mistakes occurring in arranging and setting up the type is reduced to a minimum.

According to a modification of my said invention, in lieu of arranging the month-dating type as hereinbefore described, I provide a second disk, K, Fig. 8, round the periphery of which I arrange the necessary type—that is to say, a series of twelve letters or sets of letters representing the twelve months in the year. I mount the said disk upon the spindle c' and at the side of the day-dating disk C.

In altering the month as required the disk K is moved round until the required month is in the necessary position, a pin being provided which engages in holes arranged round the side of the disk to hold it in position, as described with reference to the disk C.

The type upon the hereinbefore described disks may be cast in one with the said disks, as shown in Figs. 1 and 3, or the type may be formed of separate type-pieces let into the periphery of the disks, as shown in Fig. 9.

The letters or figures upon the type may be cast in one with the body of the type, or they may be formed of pins of steel or other wire, which make a dotted impression upon the ticket to be stamped, as shown in the detailed views, Fig. 10.

The arrangement of the parts of the apparatus admits of the spindle g being continued through the blocks or frames B G in one piece, instead of its being divided, as is unavoidable according to the construction of the ordinary machines.

It is obvious that disks arranged in the manner hereinbefore described may also be used for numbering railway-tickets.

I claim as my invention—

1. In a hand-stamp, the combination of the frame and the type-carrying block pivoted thereto with a block, G, pivoted at one end to the said type-carrying block and adapted to bear at the other on a fixed part of the frame, substantially as set forth.

2. The combination of the frame and the pivoted block B, carrying the type and movable inking-ribbon, with a block, G, pivoted to the said block B, and having an aperture, g^2 , as and for the purpose described.

3. In a hand-stamp, the block B, having arms b b' , with a numbering disk or disks mounted on a spindle between said arms, and with type adapted to recesses in the end of one or both said arms, retaining-plates e' , and thumb-screws, all substantially as specified.

4. In a hand-stamp, the combination of the pivoted type-carrying block and inking-ribbon reels with a ratchet-wheel mounted on the spindle of one of said reels, a pawl-holder carrying a pawl adapted to said ratchet, an inclined plane or rod adapted to act on said holder as the type-block is moved, and devices, substantially as described, for returning the holder to its normal position, all as set forth.
- 5

In witness whereof I have signed my name to this specification in the presence of two subscribing witnesses.

JAMES ROBERT ROBINSON.
